UNITED STATES PATENT OFFICE.

BOY FRIEDRICH BASTIANSEN, OF APENRADE, GERMANY.

STEAM-OVERHEATING APPARATUS.

SPECIFICATION forming part of Letters Patent No. 689,276, dated December 17, 1901.

Application filed April 17, 1900. Serial No. 13,204. (No model.)

chamber *h*; and the conduits *b*, *d*, conveying steam to the inlet ends and from the outlet ends of said ranges of superheating-pipes, substantially as and for the purposes set forth.

3. The combination of the heating-chamber *h*; U-shaped superheating-pipes *r* having screw-threaded ends; the plate *p*, external to the chamber *h* and from which the pipes *r* are suspended in said chamber; conical nuts *u*, *u*, mounted on the threaded ends of the pipes *r* above and below the plate *p* and fit-

ting seats prepared for them in the upper and lower faces of said plate; and suitable conduits *b*, *d*, conveying steam to the inlet ends and from the outlet ends of said superheating-pipes, substantially as set forth. 15

In witness whereof I subscribe my signature in presence of two witnesses.

BOY FRIEDRICH BASTIANSEN.

Witnesses:

GEORG HAUSCHILD, 15
E. H. L. MUMMENHOFF.
